Patented Nov. 9, 1976

242,261

SMOKER'S PIPE

William Edward Ornsby, Crook, England, assignor to Ornsby Pipe Company Limited, Crook, England

Filed Jan. 6, 1975, Ser. No. 538,720

Term of patent 14 years
The term of this patent subsequent to Nov. 9, 1990, has been disclaimed

Int. Cl. D27—02

U.S. Cl. D27—3

FIG. 1 is a side elevational view of a smoker's pipe showing my new design;

FIG. 2 is a front elevational view;

FIG. 3 is a rear elevational view;

FIG. 4 is an underneath plan view;

FIG. 5 is a top plan view;

FIG. 6 is a perspective view, partly from the front and partly from above.

I claim:

The ornamental design for a smoker's pipe, as shown.
